FOUNTAIN.

No. 15,637.

Patented Dec. 23, 1884.

UNITED STATES PATENT OFFICE.

JONATHAN MOORE, OF BROOKLYN, NEW YORK, ASSIGNOR TO THE NORTH AMERICAN IRON WORKS, OF SAME PLACE.

DESIGN FOR A FOUNTAIN.

SPECIFICATION forming part of Design No. 15,637, dated December 23, 1884.

Application filed September 20, 1884. Term of patent 14 years.

To all whom it may concern:

Be it known that I, JONATHAN MOORE, of Brooklyn, in the county of Kings and State of New York, have invented or produced a Design for a Fountain, of which the following is a specification.

In the annexed representation, Figure 1 shows the lower basin or pool, the first column, and the elevated basin upon the same; and Fig. 2 represents the second and third columns and their elevated basins and the top ornaments.

The pool or basin A has a flaring rim with arrow, scroll, and knob ornaments, as at b. The base C of the column D is in imitation of rock-work, from which rises the column D, the surface of which resembles the trunk of a tree with the branches cut off closely. The surface is also ornamented with imitation stems and leaves and ferns, as shown. Storks at E are represented as upon the base of the column, said storks having spread wings and curved necks, with their heads elevated, the jet-tubes for water being in their mouths. The basin F upon the upper end of the column D is in imitation of rustic work, with stems and leaves, and a leaflet-edge at f, as shown. The second column, G, and third column, H, are similar in design to the column D, only smaller, the surface in each instance imitating the trunk of a tree, as shown. The upper basins, K L, are similar in design to the basin F, only smaller, and ornamented in imitation of rustic work, as shown. The top ornament, R, is 35 a representation of a stork upon a clump of

leaves and reeds, as shown. The portion of the fountain shown in Fig. 2 rests upon the portion of the fountain shown in Fig. 1.

I claim—

1. In a design for a fountain, the basin or pool A, with the flaring rim having arrow, scroll, and knob ornaments, as shown. 40
2. In a design for a fountain, the base C, in imitation of rock-work, and the column D, resembling the trunk of a tree, ornamented as shown. 45
3. In a design for a fountain, the basin with stems, branches, and leaves upon the under surface, and leaflet-edge, substantially as shown. 50
4. In a design for a fountain, the columns G H, in imitation of the trunks of trees, and the basins upon such columns, substantially as represented. 55
5. In the design for a fountain, the ornament R, consisting of the representation of a stork, with leaves and reeds, substantially as shown. 60
6. In the design for a fountain, the ornaments E at the base of the fountain, representing storks with spread wings and curved necks, heads elevated, and standing independent of support from the column D, substantially as shown.

Signed by me this 4th day of August, A. D. 1884.

JONATHAN MOORE.

Witnesses:

GEORGE W. MOORE,
ALFD. MASFORD.
